PLANT WATER BOTTLE

Joseph Cefalde, 29 Millet Ave., Youngstown, Ohio

Filed June 24, 1965, Ser. No. 85,894

Term of patent 14 years

(Cl. D35—1)

I claim:

The ornamental design for a plant water bottle, as shown.
